UNITED STATES PATENT OFFICE.

FRANK F. FISCHER, OF OMAHA, NEBRASKA.

AUDITORIUM-CHAIR.

1,247,521.

Specification of Letters Patent. Patented Nov. 20, 1917.

Application filed March 27, 1917. Serial No. 157,778.

To all whom it may concern:

Be it known that I, FRANK F. FISCHER, a citizen of the United States, residing at Omaha, in the county of Douglas and State 5 of Nebraska, have invented certain new and useful Improvements in Auditorium-Chairs; and I do hereby declare the following to be a full, clear, and exact description of the invention, such as will enable others skilled 10 in the art to which it appertains to make and use the same.

This invention relates to theater or auditorium chairs, and particularly to a sliding seat attachment for chairs or benches 15 whereby the seat of the chair may be rendered slideable to and fro in a substantially horizontal plane.

It is one of the objects of my present invention to provide an attachment for converting a fixed seat of an ordinary auditorium, opera or theater chair into a seat which may be reciprocated while in use by an auditor so as to permit the movement of persons 20 to and fro along the narrow space in front 25 of a seat or seats in a row behind the backs of the next row of seats in advance.

It is indeed very objectionable in auditoriums where persons are practically constantly moving to and fro between the rows 30 of chairs or seats, this requiring the occupants of the seats to either rise or partly rise so as to afford an increased space between the rows for this movement of the auditors, and to overcome this objectionable necessity 35 for arising from the seat my present invention provides means which may be readily attached to chair or seat structures already installed and in use so that the seats of the chairs may be pushed to the rear as persons 40 pass in front of the auditors who are seated in the rows.

Another object of the invention is to provide means for preventing injury to the persons or occupants of seats in successive 45 rows of chairs so that when the seat of the chair, as herein contemplated, is pushed rearwardly by one occupant to permit a person to pass in front of him, the chair seat at it is pushed rearwardly will be prevented from injuring by forcible contact 50 with the limbs of the persons occupying the seats in the rear.

To this end a feature of the invention consists in providing a cushioning bumper

appropriately fixed to the rear of the seat, 55 this bumper being adapted, if the seat is moved sufficiently far to the rear, to cushion the blow of the seat upon the occupant at the rear.

A further object of the invention is to provide a slideable seat structure which will permit the seat to be slid from a position somewhat in front of the fixed chair frame to one sufficiently in the rear thereof to give maximum passageway in front of the occupant of the chair to allow others to pass, and which also is provided with means to automatically latch the chair in an intermediate position between its front and rear limits of movement, and in which position 70 the chair seat is held with its front in substantial alignment with the front of the fixed chair frame or structure.

It is another object of the invention to provide such a latching means as will hold the chair seat yieldably in unoccupied and partly retracted position, but will readily yield to permit the seat to move forwardly as soon as it is occupied, the weight of the occupant causing the chair seat to move forwardly to its limit of movement.

Another important object of the present invention is to provide an attachment which may be readily connected to chair, or seat, or bench structures which are already existent and installed, and therefore a feature of the invention consists in the provision of a pair of complementary upper and lower track members, one of which is adapted to be readily attached to the fixed frame of the 90 seat structure, and the other of which is adapted to be as readily applied to the seat of the structure so that the latter is slidably connected to the fixed structure of the chair.

With these and other objects in view, as 95 will be made manifest in the following specification, one embodiment of my invention is illustrated in the drawings and set forth in the following specification, in which drawing:

Figure 1 is a perspective view of the attachment as applied to a chair frame which is shown in dotted lines and as attached to a seat frame and back illustrated in full lines.

Fig. 2 is a perspective view of the detached and separated complementary track members of one pair of the attachments.

Fig. 3 is a side elevation of the inside face of a fixed chair frame showing the track attachment secured thereto and to a chair seat structure, the track attachment being 5 shown partly in vertical sectional view, and in which the seat is shown as projected in its foremost position.

Fig. 4 is a similar detail view, partly in elevation and partly in section, showing the 10 seat as pushed or retracted to its intermediate position and yieldingly held by its spring latch, and showing in dotted lines the rearmost position of the seat.

Fig. 5 is a transverse section showing in 15 detail the construction of the complementary attachable track members.

It is to be understood that my present invention contemplates an attachment for 20 slidably connecting a seat of a chair to the relatively fixed frame members of the chair, and which attachment is adapted to be readily and easily connected to the respective members by the use of simple fastening means, and the attachment is capable of use 25 in combination with various forms of chair frames and seats without requiring any other alteration or change upon these members more than to provide the necessary bolt holes to receive bolts or other suitable fastening means by which the attachable connection may be secured to the respective members. Therefore in the following specification and in the drawing there is disclosed a simple form of theater chair fixed frame 30 structure 2 of any appropriate design and proportion, and a series of these chair frames 2 may be rigidly connected in suitable organization in a row through means of a longitudinal tie or brace 3, shown in dotted 35 lines in Fig. 1, and in section in Figs. 3 and 4. The present invention contemplates an attachment whereby the seat 5, which may be of any suitable construction, may be slidably connected to the rigid frame members 40 2, for instance, and this attachment is illustrated as comprising a set of pairs of complementary track members, each of which pairs includes a track member 6 adapted to be rigidly secured as by bolting, screwing, 45 or by other means to the side member 2 of the fixed chair frame at any suitable position, and preferably in an inclined plane, the angle of which will be just sufficient to cause the chair seat 5 to automatically move 50 forward under the weight of the person or occupant of the chair. A simple, practicable, and very inexpensive embodiment of the attachment is herein illustrated in which the member 6 is shown as consisting of a 55 substantially channel-shaped member of suitable length and proportions, and of metal of appropriate thickness, one of the flanges of the member 6 extending upwardly as at 7 a suitable height to provide ready 60 application and fastening of bolts, screws 65 or other suitable means as 8 which may be passed through apertures 9 provided for their reception, and which are formed at suitable intervals along the upwardly projecting or wider flange 7 of the track member 6. The lower portion of this member is provided with a transverse web member 9' of sufficient width to form a space between the fastening cheek or flange 7, and a front or inner parallel flange 10 for the 70 reception of anti-friction rollers 11 of suitable type and construction which may be provided with integral spindles 12 at their ends or may be made hollow and be mounted upon pins which may be passed therethrough 75 and seated in opposite apertures 13 which are provided at desired intervals along the length of the track member. The track member 6 may either be formed in a blank in flat form and suitably perforated with 80 the apertures 9 and 13, to provide respectively for the fastening bolts and for the stems or spindles of the rollers 11, and then the blank may be folded to the form or outline indicated in Fig. 5 so as to embrace the 85 interposed rollers 11 when these are assembled in proper position thereon, or the track members 6 may be rolled into the proper cross sectional form and the spindles 12 of the rollers then introduced between the parallel flange members 7 and 10 and these members sprung again closed over the ends of the spindle to securely engage the same 90 and prevent their removal. Complementary to the fixed track member 6 there is provided also a movable track member shown in the form of a piece of channel iron 15 of suitable length and thickness, this channel iron preferably having a width between 95 its side flanges substantially equal to the 100 distance between the top of the rollers 11 and the bottom surfaces of the web 9 of the roller bearing channel member 6 so that when the track member 15 is applied with 105 its flanges embracing the rollers and the 110 bottom of the web 9, as shown in Fig. 5, relative movement vertically as between these members is practically prohibited, these being designed to have a relatively 115 snug sliding relation one to the other. To provide for the attachment of the movable track member 15 to the seat of the chair structure, one of the flanges of the channel member 15 is adapted to be perforated as 120 at 16, Fig. 2, for the reception of rivets, bolts, screws or other fastening means, whereby this member may be connected in proper position to the chair seat construction. As shown in Fig. 1, the chair seat involves a suitable frame construction 20 having a back frame 21 and a pair of forwardly extending side members 22 arranged in a common plane, and to which there may be secured in any suitable manner the seat 25 of the chair, as illustrated in dotted lines 30

at 5. In this embodiment of my invention the slidable track member 15 is shown as secured to the parallel side members 22 of the chair seat frame 20, and this assembled organization is adapted to be mounted upon the inclined channel members 6 when these have been securely mounted in their respective positions upon the inner surface of the opposite side fixed frames 2 of the chair structure.

To provide for the limit of movement forwardly and rearwardly of the sliding chair seat 5 upon its fixed tracks 6, any suitable form of stop means may be employed, and this is readily accomplished in the present instance by folding downwardly at the rear end of each of the movable track members 15 a lug 15' which is adapted to strike against the rear end of the fixed track 6 when the chair seat has been slid forwardly to the limit. The stopping of the sliding movement of the chair seat rearwardly may be accomplished by the provision of adjustable stop locks or lugs as shown in Fig. 5, one of which is shown at 25 as fastened to the bottom of the fixed track member 6, and the other of which is attached to the bottom of the movable track member 15 so that upon rearward movement of the latter member its stop 26 will abut against the stop 25 on the fixed member 6 which is attached to the chair frame.

One of the important features of my present invention resides in providing means for protecting occupants of chairs in the successive rows against injury by contact with a seat which may be slid rearwardly by its occupant when he desires to permit a person to pass in front of him, and to accomplish this a suitable bumper or cushion is provided. This cushion may be located at any desirable position upon the rear portion of the slidable structure of the chair and is conveniently disposed as shown in Fig. 3 by attachment to the downwardly turned ears or stop lugs 15' at the ends of the sliding member 15. The bumper may consist of a cushion 27 of suitable material mounted upon a transverse bar 28 which may be secured to the track member 15 as shown.

Another feature of my invention resides in providing means for yieldably holding a seat in an intermediate position between the chair frame 2 so that as an occupant of a chair arises to leave a seat he may push the chair seat rearwardly into alinement with the front of the chair arm or leg of the frame 2, as shown in Fig. 4, and thus materially increase the width of the aisle between the successive rows of chairs. This is accomplished by providing any suitable form of yieldable latch as 30, Figs. 4 and 5, one of which is shown as secured to one of the tracks 15, or it may be secured to any portion of the movable seat structure. The

latch 30 is in the form of a spring adapted to pass over and yieldably engage the longitudinally extending brace 3 which is conveniently disposed and is utilized to brace the several chairs in the row. Preferably the strength of the latching device, as 30, is just sufficient to retain the chair in its intermediate position against the force of gravity tending to cause the chair to roll forwardly down the inclined fixed tracks 6, and the spring is adapted to automatically yield when the seat is occupied by a person, and thus permit the chair to slide freely forwardly to its normal front position.

When the side frames 2 are disposed radially in an arc or angularly to each other, the seat tracks are, of course, set in parallel relation by appropriate connection to the frames and to the seats so as to avoid binding of the parts. This may be accomplished by the use of washers on the fastening bolts.

What I claim is:

1. An auditorium chair having side frames, a seat slidably mounted upon the frames, means for limiting the movement thereof to the front and rear, a brace connecting the frames and yieldable means on the seat bottom for temporarily engaging the brace and holding the seat in an intermediate approximately alined position at its front edge with the front elements of the side frames.

2. An auditorium chair having side frames, a seat freely slidably mounted in an inclined plane upon the frames, means for limiting the movement thereof to the front and rear, and yieldable means for temporarily holding the seat in an intermediate approximately alined position at its front edge with the front elements of the side frames, said means operative to readily release the seat so that it will automatically run forward when occupied.

3. An attachment for seat structures, comprising a lower channel-shaped track member attachable to a fixed element of the structure, a complementary channel-shaped upper member attachable to a seat to slidably connect the seat and the fixed structure and embracing the lower member, and anti-friction means interposed between said members, and journaled in the lower member, and a stop carried by the bottom flange of the upper track to engage complementary fixed stops.

4. An attachment for seat structures, comprising a channel-shaped lower track attachable by one flange to a fixed chair structure, and having transverse parallel rollers journaled between its flanges, and a channel-shaped sliding track attachable to a chair seat and adjustable upon the complementary fixed tracks so as to embrace the bottom thereof and overlap and run upon the rollers.

5. An attachment for seat structures, comprising a channel-shaped lower track attachable by one flange to a fixed chair structure, and having transverse parallel rollers journaled between its flanges, and a channel-shaped sliding track attachable to a chair seat and adjustable upon the complementary

fixed tracks so as to embrace the bottom thereof and overlap and run upon the rollers, the web of the moving member forming 10 a stop against lateral movement of the seat.

In testimony whereof I affix my signature.

FRANK F. FISCHER.
